CPC A61C 7/02; A61C 7/04; A61C 7/023; A61C 7/146; A61C 3/00; A61C 3/10; A61C 3/14; A61C 3/16; B25B 7/00; B25B 7/02; B25B 7/04; B25B 7/10

The ornamental design for a handle for an orthodontic instrument, as shown and described.

See application file for complete search history.

DESCRIPTION(56) **References Cited**

FIG. 1 is a perspective view of an embodiment of a handle for an orthodontic instrument;

U.S. PATENT DOCUMENTS

FIG. 2 is a front view thereof;

536,166 A * 3/1895 Angle A61C 7/04
 433/4

FIG. 3 is a back view thereof;

1,626,226 A 4/1927 Osias
 1,850,268 A 3/1932 Kulp et al.

FIG. 4 is a left side view thereof;

FIG. 5 is a top view thereof;

FIG. 6 is a right side view thereof; and,

FIG. 7 is a bottom view thereof.

The dash-dot-dash broken lines illustrates the bounds of the claim. The broken lines showing of various portions, other elements in the Figures are for the purpose of illustrating unclaimed portions and form no part of the claimed design. The claimed design includes two surface textures, namely, polished and brushed surface textures with the stippling indicating a brush surface texture.
